FIG. 2

UNITED STATES PATENT AND TRADEMARK OFFICE
CERTIFICATE OF CORRECTION

PATENT NO. : Des. 489,778 S

Page 1 of 3

APPLICATION NO. : 29/179926

DATED : May 11, 2004

INVENTOR(S) : Wen-Ta Fan, Christopher M. Hancock and Mark G. Hecox

It is certified that error appears in the above-identified patent and that said Letters Patent is hereby corrected as shown below:

The title page should be deleted to appear as per attached title page.

The sheet of drawing consisting of figure 1 should be deleted as per attached figure 1.

Signed and Sealed this

Fourth Day of September, 2007

A handwritten signature in black ink, appearing to read "Jon W. Dudas", is centered within a rectangular box with a dotted background.
